CLAIM

The ornamental design for a dual planter box, as shown.

DESCRIPTION

FIG. 1 is a perspective view taken from the top, front and left side of a dual planter box showing my new design;

FIG. 2 is a top plan view thereof;

FIG. 3 is a right side elevational view thereof, the left side being substantially a mirror image thereto;

FIG. 4 is a rear elevational view thereof, the front elevational view being substantially a mirror image thereto; and

FIG. 5 is a bottom plan view thereof.

FIG. 1

FIG. 2

FIG. 4

FIG. 3

FIG. 5
